LABYRINTH STIFFENER

James R. Mondt, Warren, Mich., assignor to General Motors Corporation, Detroit, Mich., a corporation of Delaware

Filed Dec. 18, 1962, Ser. No. 245,577
5 Claims. (Cl. 165—10)

My invention relates to rotary regenerators, that is, devices in which a porous annular body, called a matrix, rotates slowly so that each part of the matrix passes alternately through two spaces where it is exposed to gases at different temperatures, the matrix carrying heat from the hotter to the cooler gas. In such devices, a seal is provided where the matrix passes from one space to the other through a diaphragm or bulkhead. Sealing is one of the difficult problems in such regenerators, since there ordinarily is a very considerable pressure drop from one space to the other in installations such as gas turbines. Because of the changes of temperature of the gases as they flow through the matrix, the matrix has a temperature gradient. Because of the temperature gradient, there is differential expansion which may, and ordinarily does, cause a distortion of the matrix so that it becomes slightly dished, or barrel-shaped, or spool-shaped. Of course, this distortion is very slight, but slight clearances at the seals can cause very wasteful leakage.

In response to this problem various efforts have been made, with considerable success, to provide a seal which distorts along with the matrix. Another approach is to construct a matrix so that the thermal distortion is eliminated or minimized. My invention relates to a structure minimizing distortion of the matrix, and particularly of the portions of the matrix which cooperate with the diaphragm seals. While the invention is applicable to both axial-flow and radial-flow regenerators, its preferred embodiment is in a radial-flow regenerator having two seals which surround the matrix at the two points where it passes through a diaphragm separating one gas space from the other, such as is described in United States patent applications Serial No. 559,390, filed January 16, 1956, (now Patent No. 3,057,604) and Serial No. 156,599, filed December 4, 1961.

The principal object of the invention is to decrease the leakage of the seals of rotary regenerators and, therefore, improve the efficiency of power plants incorporating such regenerators. The nature of the invention and its advantages will be clear from the succeeding detailed description of the preferred embodiment thereof, with reference to the accompanying drawings.

FIGURE 1 is a rather schematic cutaway view of a rotary regenerator embodying the invention, the view being taken on a plane perpendicular to the axis of rotation.

FIGURE 2 is an enlarged partial view of the matrix taken in the same plane as FIGURE 1, with parts cut away.

FIGURE 3 is a cross-section of the matrix taken on the plane indicated by the line 3—3 of FIGURE 2.

FIGURE 1 may be regarded as a simplified representation of the application of my invention to the regenerator of a gas turbine engine such as that described in U.S. patent application Serial No. 559,475, filed January 16, 1956 (now abandoned). In such an engine, a regenerator matrix 9 is suitably supported in a housing 10 for rotation about an axis A so that it passes twice through a bulkhead or diaphragm 11. Main seals 13 and 14 surround the matrix where it passes through the diaphragm. The means to support the matrix for rotation about the axis and to locate the seals 13 and 14 are immaterial to this invention and will not be described.

2

Approximately one third of the matrix is to the left of the diaphragm, moving through a space which is divided by the matrix into a cool air zone 18 which may be supplied by the compressor of the gas turbine engine and a hot air zone 19 into which the air flows through the matrix. Combustion chambers (not illustrated) connected to the hot air zone 19 discharge through a turbine (not illustrated) into a hot gas zone 23 within the matrix at the other side of the diaphragm, from which the exhaust gas flows through the matrix to space 25 from which it is discharged to the atmosphere.

Referring now also to FIGURES 2 and 3 for the preferred structure, the matrix 9 is of an annular drum shape having two rims 27, each of which may include a ring or track 28 by which the matrix is supported and guided and a ring gear 29 by which it is driven. Stiffeners 31 of relatively heavy section are spaced regularly around the periphery of the drum, extending from one rim to the other to couple the rims together rigidly. The stiffeners have lugs 33 extending from their ends received in circumferential grooves in the inner faces of the rims and held there by pins 34 which are inserted before the ring 28 is shrunk into place.

The spaces between the stiffeners 31 and extending from one rim to the other are filled with porous heat transfer material which consists of two types of elements. The first of these are regularly spaced seal elements 36. Between each two seal elements there is a stack or pack of heat transfer elements 37 which may be called a core. It will be noted that the seal elements 36 have opposite marginal portions which extend radially from the elements 37. The elements 37 may be regarded as the core of the matrix, and the elements 36 and 37 together constitute heat transfer material. These elements may be thin corrugated plates with the corrugations extending radially of the matrix so that small passages for air flow are defined between adjacent plates and heat is readily exchanged between the air or gas and the thin plates of the heat transfer material. If desired, alternative plates of the heat transfer material may be flat and corrugated; or other forms of heat exchange material, including those described in United States Patent No. 2,937,010, may be employed. In the preferred structure according to this invention the core elements 37 are corrugated sheets having the same end configuration as the stiffeners 31 so as to fit within the grooves in the rims. Each labyrinth element 36 comprises a plate or lamina 40, corrugated so that the corrugations extend radially of the matrix, and with tabs 41 extending from the ends of the lamina to enter the grooves in the rim. Each seal element 36 also includes two bars 42 and 43 which extend across the length of the lamina, preferably nearer the outer or cooler edge thereof, and which are spot-welded or seam-welded to the lamina 40 so as to provide as nearly as possible a single rigid beam structure. It will be appreciated, of course, that the thin corrugated plate 40 has almost no stiffness. In other words, it can be deformed arcuately in its own plane by expanding the corrugations toward one edge and contracting the corrugations toward the other edge. With the bars 42 and 43 welded to the peaks of each corrugation there is a relatively stiff structure involving the bars and the plate 40. If all these parts were of the same material, the temperature gradient in the direction from the upper edge to the lower edge in FIGURES 2 and 3 would operate to cause arcuate deformation of the bars and lamina. In other words, the hotter bar 43 would expand more than the cooler bar 42 and they would bow upwardly of the element as seen in FIGURE 3 and the very slight resistance of the corrugated sheet itself would make very little difference. In other words, the thermal expansion and the dimensions and spacing of the bars would determine the amount of

distortion of the seal element 36. According to my invention, by proper selection of materials for the bars 42 and 43, this distortion may be eliminated or minimized.

Control of the configuration of the seal element can be obtained by employing two bars 42 and 43 which are of different coefficients of thermal expansion so that they expand the same amount linearly in response to the different temperatures to which they are subjected. (This is a correct statement subject to a qualification which will be mentioned.) With the two bars welded or brazed to the corrugations across the seal element 36 and at predetermined distances from the matrix axis, the bars remain straight and maintain the edges of the plate straight as well. If one bar expanded more than the other, there would, of course, be bowing, or a tendency to bow which could be counteracted by force.

It is clear that, considering the seal elements 36 alone, if selection of the materials for bars 42 and 43 is such that their temperature coefficients of expansion are related to each other inversely as the temperature rises of the two bars, a structure which is invariant in contour with temperature is provided. It merely expands as it becomes hotter. If the heat transfer material or core material 37 has no tendency to distort as, for example, if it is particulate matter, this is the end to the problem. However, if the core is made up of plates, even though they are very flexible dimensionally such as the corrugated sheets of shim material illustrated, these will have a tendency to bow and, by frictional interaction with the seal plates, will tend to bow them also.

By increasing the difference between the expansion coefficients of the bars 42 and 43 so that the seal plate 36 tends to have a reverse curvature to the normal, this factor due to loading by the core can also be compensated for. An analysis of this factor is difficult, if not impossible, but the correction can be made empirically by trial and error.

The foregoing will explain the principles and advantages of the preferred embodiment of the invention. By providing a matrix which is substantially invariant in cross-section as temperature changes, a simple diaphragm seal of fixed shape can be used without any considerable leakage past the diaphragm.

By way of instructive example, major dimensions of one labyrinth element embodying the invention may be stated. The corrugated sheet 40 is approximately 8" by 2", overall, including the tabs 41, is made of 0.003" type 321 stainless steel with corrugations of 0.04" pitch approximately 0.0125 deep. Bar 43 is stainless steel, type 430, 0.044" x 0.25", and bar 42 is stainless steel, type 321, 0.064" x 0.25". Bar 42 is thicker than bar 43 because there is more room at the greater radius. The relative location of the bars is as shown in FIGURE 3.

The description of the preferred embodiment of the invention for the purpose of explaining the principles thereof is not to be considered as limiting the invention, since many modifications may be made by the exercise of skill in the art.

I claim:

1. An annular regenerator matrix comprising an annular body defining passages for the flow of fluids to

establish a temperature gradient between the opposite sides of said body, said annular body including sealing plates spaced around the matrix axis and lying in planes extending along the latter, each of said sealing plates comprising a sheet with opposite marginal portions extending from the annular body for sealing purposes and having a low effective moment of inertia in a plane normal to said opposite sides and transverse to the sheet, two parallel and spaced bars of material thicker than that of the sheet and each being fixed to the latter a predetermined distance from the matrix axis, the aggregate of said bars having a high effective moment of inertia in the above-recited plane transverse to the sheet, and the material of one of said bars lying toward one side of said body having a coefficient of thermal expansion lower than that of the other bar which lies toward the other side of said body.

2. A rotary regenerator matrix comprising an annular body having an axis and opposite sides, said body defining 20 passages for the flow of fluids to effect a temperature gradient from one of said sides to the other and including sealing plates extending from one said side to the other substantially parallel to the direction of fluid flow, said body also including porous material interposed between 25 each of said sealing plates and the adjacent sealing plates, each of the sealing plates comprising a sheet having opposite marginal portions projecting slightly from the said porous material at said sides, and two spaced bars fixed rigidly to the sheet and extending generally parallel to the said sides, the sheet having a low effective moment 30 of inertia in a plane normal to said sides and transverse to the sheet and the aggregate of said bars having a high effective moment of inertia in the same plane compared to the sheet so that the effective moment of inertia of the sealing plate in the said plane is due primarily to the bars and due only to a minor extent to the sheet, the materials of said bars having different coefficients of thermal expansion to counteract the tendency of the sheet to bow in response to heat effecting the said temperature gradient, the bar lying toward the hotter side of the matrix having a lower coefficient than the other bar.

3. A matrix as recited in claim 2 in which the said coefficients are so selected that the thermal expansions of the bars during heat exchange operation are approximately equal.

4. A matrix as recited in claim 2 in which the thermal expansion of the bars during operation serve to compensate for the distortion transmitting effect of said porous material and in maintaining the said marginal portions of said sealing plates along lines effective for sealing.

5. A matrix as recited in claim 2 in which the bars are thicker than the sheet in the dimension perpendicular to the sheet and are much narrower than the sheet in the direction parallel to the sheet.
